UNITED STATES PATENT OFFICE.

JOHN O. NEIKIRK, OF LOMBARD, ILLINOIS, ASSIGNOR TO RODGER BALLAST CAR COMPANY, OF CHICAGO, ILLINOIS, A CORPORATION OF MAINE.

DOOR-OPERATING MECHANISM.

1,374,516.

Specification of Letters Patent. Patented Apr. 12, 1921.

Application filed December 14, 1918. Serial No. 266,729.

To all whom it may concern:

Be it known that I, JOHN O. NEIKIRK, a citizen of the United States, residing at Lombard, in the county of Dupage and State 5 of Illinois, have invented certain new and useful Improvements in Door-Operating Mechanism, of which the following is a specification.

This invention relates to door operating 10 mechanism.

In the operation of the dump doors, and particularly those of ballast cars, there is great advantage in controlling the opening of these doors in a step by step manner 15 whereby said doors may be opened gradually the desired amount to permit the required flow of material for ballast work. I am aware of the fact that dump doors of ballast cars heretofore have been provided with 20 means whereby the same may be gradually opened in a step by step manner, but the mechanism thus far used may be simplified and the positive control of the dump doors facilitated.

Accordingly, the object of this invention 25 is to simplify and improve the operation and control of dump doors of dump cars, and particularly ballast cars, and to provide improved operating and control mechanism 30 for such doors.

This and other objects are accomplished by means of the mechanism disclosed on the accompanying sheets of drawings, in which—

Figure 1 is a fragmentary side elevation 35 of a ballast car embodying my invention;

Fig. 2 is an end view of the same car;

Fig. 3 is a transverse sectional view of the same car taken intermediate the trucks;

Fig. 4 is a detail view showing the operating shaft in side elevation and my door operating and control mechanism in end elevation;

Fig. 5 is a detail view of the same arrangement, showing the control and operating 45 mechanism in side elevation;

Fig. 6 is a view of the same operating and control mechanism taken in the plane of line 6—6 of Fig. 5;

Fig. 7 is a detail plan view of a modified 50 form of operating and control mechanism; and,

Fig. 8 is a side elevation of the same.

The various novel features of my inven-

tion will be apparent from the following description and drawings and will be particularly pointed out in the appended claims.

Referring to the figures of the drawings, it will be noted that I have illustrated my invention in connection with a Hart convertible car, including a body having sides 10, 55 ends 11 and a floor, including longitudinally extending doors 12, 13, 14 and 15, which when in closed position lie in a horizontal plane to form the flat bottom of the car. The sides of the car include swinging members 16 and 17 which, when supported in an inclined position, form, with the floor doors 13 and 14, side walls of a central hopper, the bottom of which is formed by a stationary portion 18 and a dump door 19 pivotally 60 connected at 20, the door 19, or doors, if it is desired to have a plurality of doors in longitudinal alignment, being provided with operating mechanism including a shaft 21, around which one end of a chain 22 is 65 wound, the other end of the chain being operatively connected to the door 19. In addition to the central dump doors 19 for dumping the ballast material between the tracks, the floor dump doors 12 and 15, 70 75 which are pivoted at their inner ends, may be lowered or swung into an open position to dump ballast material to the sides of the track. The door operating mechanism for the dump doors 12 and 15 includes shafts 23 and 24, respectively, around which one end of each of a plurality of chains 25 pass, the 80 opposite end of said chains being connected to said dump doors.

This invention relates primarily to the 90 door operating and control mechanism. In view of the fact that the door operating and control mechanism is the same for all the dump doors 12, 15 and 19, only one will be specifically described, it being understood 95 that such mechanism in each case is applied to the operating shafts 21, 23 and 24. Referring to Figs. 4, 5 and 6, it will be noted that the operating shaft 21 has securely or rigidly mounted thereon a ratchet wheel 26, including a central disk having integrally-formed stop members 27 on opposite sides thereof, the series of stop members on one side of the disk being staggered with respect to the series of stop members on the other side. 100 Cooperating with the stop members 27 are

jaws 28 of a pawl 29 pivotally connected at 30 to any suitable bracket 31, the outer end of the pawl having a socket portion 32 for the reception of an operating handle where-
5 by the pawl member 29 may be oscillated back and forth in a manner such that its jaws 28 may function with the stop members 27. As stated hereinabove, it is de-
sirable to open the dump doors, or permit
10 the doors to drop, increment by increment in a controlled manner, whereby the outward flow of the ballast, or other material, may be controlled to a nicety.

Let it be assumed that any one of the
15 dump doors is in its closed position and it is desired to open the same a certain predetermined amount to permit a given flow of ballast material. With the dump door in its closed position one of the jaws 28 is in
20 engagement with the upper surface of one of the stop members 27, thereby holding the door in said position, it being understood that the load in the car has a tendency to force the door open and through the medium of
25 the operating chain to rotate the operating shaft in a clockwise direction. Referring particularly to Fig. 6, it will be noted that one of the jaws 28 is in a position over one of the stop members 27, preventing the
30 ratchet wheel 26 and the shaft 21 from rotating in a clockwise direction, as viewed in Fig. 5. To permit the door to lower one step, the pawl 29 is shifted laterally so that the jaw 28 in question moves away from the
35 disk 26 and out of engagement with the associated stop member 27 to permit the shaft to rotate one set in a clockwise direction, thereby permitting the door to open a given amount. However, this rotative movement
40 is then arrested by the other jaw 28 which moves toward the disk 27 and into the path of movement of the next succeeding stop member 27 on the opposite side of the disk 26. To permit a further opening movement
45 of the dump door, the pawl is moved in the opposite direction. This oscillatory movement of the pawl 29 is continued, permitting the dump door to open step by step until the same has been opened the desired amount to
50 permit the ballast or other dumpable material to flow in accordance with requirements.

After the load has been dumped, the dump doors are closed by means of a lever 33 loosely mounted upon the operating shaft and carrying a pivotally mounted pawl 34 which co-operates with a ratchet wheel 35 fixed to the shaft and normally held thereon by a cotter 36. The lever 33 is normally supported by an arm 37 secured to a plate 38 which supports the bracket 31.

Referring to Figs. 7 and 8, it will be noted that I have shown a modified form of door operating and control mechanism
65 in which I have provided an integrally-

formed ratchet wheel including a plurality of disks 40 and 41 having formed on the inner sides thereof a plurality of stop members 42 which are arranged in staggered relationship. Coöoperating with the stop
70 members 42 is a pawl 43 pivotally connected at 44 to a supporting bracket 45, said pawl having at its outer end a socket portion 46 for the reception of an operating handle. As shown in Figs. 7 and 8, the pawl 43
75 is in engagement with the flat top portion of one of the stop members on the disk 40 to prevent the shaft from rotating in a clockwise direction, as shown in Fig. 8. However, if it is desired to permit the dump
80 door to open one step, the pawl member 43 is moved away from the disk 40 and out of engagement with the associated stop member 42, whereupon the door is opened
85 a given amount. At the same time, however, the pawl 43 has moved toward the disk 41 and directly into the path of movement of the next succeeding stop member
90 42, thereby arresting further movement of the operating shaft 21 and the associated door. Further step by step door opening movements may be permitted by oscillation
95 of the pawl 43. It will be noted that the pawl 43, during its lateral movements, follows a serpentine or zig-zag path formed by the stop members 42 on the disks 40 and 41. To prevent accidental movement of the pawl 41, and thereby an opening movement of the dump door, I have provided a cam locking member 47 which is pivotally mounted at 48 on a supporting plate 49, said cam being movable into engagement with one side or the other of a projection
100 50 formed on the socket portion 46 of the pawl 43. When the cam locking member 47 is in locking engagement with the pawl projections 50, it is impossible to oscillate the pawl to permit an opening movement of the dump door. A modified form of
105 locking mechanism, including a pin 51 insertible into openings which may be brought into alinement, is shown in Fig. 6. The door closing mechanism shown in Figs. 7 and 8 is identical with the door closing mechanism shown in the other figures of
110 the drawings. By means of this simple and compact door operating and control mechanism the dump doors may be operated and controlled in an improved and desirable manner to successfully meet service conditions.
115

While this operating mechanism is shown in connection with a ballast car, it is to be understood that it is applicable to any type of dump cars where the control of the door is desirable, and that it is not the intention to limit the use of the invention to ballast cars.

I claim:

1. A door operating mechanism compris-
130

ing a shaft, a member rigidly mounted upon said shaft, said member being provided with stop members in diagonal relation to each other, and means for consecutively engaging 5 said stop members.

2. A door operating mechanism comprising a shaft, a disk rigidly mounted upon said shaft, said disk being provided with stop members, each stop member being 10 diagonally arranged with relation to the adjacent stop members, and an operating lever provided with means for consecutively engaging the stop members.

3. A door operating mechanism comprising a shaft, a member mounted upon said shaft, said member being provided with a plurality of series of stop members, the stop members of one series being arranged in staggered relation to members of the adjacent 15 series, and an operating member for alternately engaging the stop members of the series.

4. A door operating mechanism including a shaft, means mounted thereon having a plurality of staggered stop members, and means for successively engaging said stop members whereby the dump door may be opened step by step to control the flow of 20 dumpable material.

5. A door operating mechanism includ-

ing a shaft, means mounted thereon having a plurality of stop members arranged in zig-zag formation, and means for engaging 35 said stop members in a given sequence whereby the dump door may be opened step by step to control the flow of dumpable material.

6. A door operating mechanism including a disk having a plurality of laterally extending stop members, and a pivotally 40 mounted laterally movable pawl for successively engaging said stop members whereby the dump door may be opened step by step to control the flow of dumpable material.

7. Dump door control mechanism including movable means with stop members arranged in zig-zag formation, and a pawl 45 movable into and out of engagement with said stop members for controlling a step by step opening movement of the door. 50

8. Dump door control mechanism including a disk having a plurality of laterally extending stop members, a pawl engageable successively with said stop members whereby the dump door may be operated step 55 by step, and means for locking said pawl in a given position.

Signed at Chicago, Illinois, this 12th day of December, 1918.

JOHN O. NEIKIRK.
